UNITED STATES PATENT OFFICE.

WALTER S. ADAMS, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

CAR TRUCK.

Application filed December 22, 1922. Serial No. 608,420.

To all whom it may concern:

Be it known that I, WALTER S. ADAMS, a citizen of the United States, and a resident of the city and county of Philadelphia and the State of Pennsylvania, have invented a certain new and useful Improvement in Car Trucks, of which the following is a specification.

This invention relates to an improvement in car trucks, and has for its object to provide a novel form of spring-supporting means which will avoid the jerky and unpleasant lateral movements of the car body; and which will remove the twisting strains usually imposed upon the leaf springs of the truck during the jerky lateral movements of the car body on rough stretches of the track.

A further object of my invention is to provide a means for connecting the car body bolster and truck springs whereby the position of said bolster and the springs with relation to one another will be uniformly maintained, and any lateral movement of the bolster will cause a uniform lateral movement of the springs.

With these objects, and other objects which may hereinafter appear, in view, I have devised the particular arrangement of parts hereinafter set forth and more particularly pointed out in the claims appended hereto.

Reference is to be had to the accompanying drawing, forming a part hereof, in which—

Figure 1 is a side elevation of a portion of a car truck, showing my improved spring suspending means, parts being shown in section to disclose construction.

Figure 2 is a plan view of a portion of the truck frame, and the spring hanger supported thereon.

Figure 3 is a sectional view on the line 3—3 of Figure 1, looking in the direction of the arrows.

Figure 4 is a front elevation of a modified form of spring hanger.

Figure 5 is a sectional view on the line

5—5 of Figure 4, looking in the direction of the arrows. 50

Figure 6 is another modified form of hanger.

Figure 7 is a transverse section of a portion of the truck, showing the bolster and its connection to the supporting spring. 55

Figure 8 is a plan view of the connecting link between the bolster and spring.

Figure 9 is a sectional view on the line 9—9 of Figure 8, looking in the direction of the arrows. 60

Figure 10 is a side elevation of the link, disclosed in Figure 8, and

Figure 11 is a sectional view on the line 11—11 of Figure 8, looking in the direction of the arrows. 65

Throughout the various views of the drawings similar reference characters designate similar parts.

In the embodiment of my invention as disclosed in Figures 1, 2, 3 and 7 to 11 inclusive, 70 the upper member of the truck side frame is indicated at 1 and the lower member of said frame is indicated at 2. The truck bolster is indicated at 3 and it is located within the truck frame in the conventional manner between a pair of cross-braces 30. The ends of the bolster are supported upon suitable coil springs 4 which rest upon a spring seat 5 carried upon a semi-elliptic leaf spring 6. 75

The spring seat 5 is disclosed in detail in Figures 7 to 11 inclusive where it will be seen that the same is provided with an upper face 31, the edge of which is provided with a wall or flange 32. The spring seat 5 is provided with a rearwardly extending channel-shaped portion 33 which lies between a pair of bars or links 34 and is secured to said bars or links 34 by means of bolts 35 extending through these links and through the portion 33 of the spring seat. 80

The spring seat is provided with downwardly extending flange portions 36 which extend over the sides of the leaf spring 6. The ends of the links or bars 34 are pivotally connected to a lug 37 on the underside of the bolster 3 by means of the bolt 38. 85

Through the foregoing arrangement, it will be seen that the leaf spring 6 and the bolster are connected in such a manner that any lateral movement of the bolster is transmitted to the spring and the bolster and spring will swing or sway in unison.

The link which connects the spring and bolster together consisting of the spring seat 5 and the links 34 also acts to hold the leaf 10 spring flat or horizontal preventing distortion or twisting movement of said spring.

The coil springs 4 act to support any light load on the car and when a heavy load is placed on the car, the under face or flange 15 39 of the bolster 3 will come into contact or rest upon the wall or flange 32 of the spring seat 5 preventing the coil springs 4 from being compressed further and transferring the load to the leaf spring 6.

20 The ends of the leaf spring 6 are supported upon a bracket or seat 7, and said bracket is provided with a pair of upwardly extending ears 8 between which a block 9 is pivoted on the bolt or pin 10.

25 At 11 is shown a U-shaped hanger which is provided on the inner side of its arched upper end with a rounded rib 12 which rests in a corresponding recess 13 provided in an enlarged portion 14 on the upper edge of the 30 side frame member 1.

The lower ends of the hanger 11 are bent or curled upwardly as at 15 to fit in corresponding depressions in the block 9.

From the foregoing, it will be apparent 35 that during side sway of the bolster, the spring 6 will, by reason of the pivot joint 10 and by reason of the free mounting of the hanger 11 on the frame, ride horizontally and the twisting stresses usually imparted to a fixed spring, will be avoided.

In Figures 4 and 5 a modified form of construction is disclosed, wherein the spring bracket or seat 7 has its ears 8 pivoted to the end of a curved link or hanger 16 by 45 the pin 17. The hanger 16 extends upwardly on one side of the frame member 1, and has its upper end curved to extend over the top of the frame member 1. At 17^a is shown the hanger-supporting bracket provided with a 50 pair of spaced lugs 18 which straddle the frame member 1 and which are secured thereto by the bolt 19. The bracket 17^a is provided with a pair of upwardly extending spaced ears 18 between which the upper 55 curved end of the hanger 16 is pivoted on a bolt or pivot 19^a.

Another modification of my invention is disclosed in Figure 6 wherein the spring supporting bracket or seat 7 has its pivot pin 20 lying within the loop or curve 22 of a substantially U-shaped hanger member 23. The hanger 23 has its upper ends inwardly curved as at 24 to lie in corresponding depressions 25 in a seat 26. The seat 26 is 60 provided on its under face with a rounded

rib 27 which rests in a corresponding depression located in an enlarged portion 28 on the upper edge of the frame member 1.

I have shown several modifications of my invention each of which shows a swinging link adapted to swing from the frame at one end and having its lower end pivotally connected to the supporting means for the leaf spring. Through this arrangement the leaf spring is retained horizontal during all 75 lateral motion.

From the foregoing it is obvious that my invention is not to be restricted to the exact embodiments shown but is broad enough to cover all structures coming within the scope 80 of the annexed claims.

Having described my invention, what I claim is:

1. In a car truck, a truck frame, a U-shaped hanger adapted to straddle the frame and extend downwardly on opposite sides thereof, said hanger having its upper end resting on said frame and free to oscillate thereon, a spring seat pivoted to the lower end of said hanger and a leaf spring having its end supported on said seat. 90

2. In a car truck, a truck frame, a hanger resting on the upper edge of said frame and having its side members extending downwardly on opposite sides thereof, said hanger being free to oscillate on said frame, a spring seat secured to the lower end of said hanger and free to swing independent of said hanger, a leaf spring having its end supported on said seat, a bolster supported by said spring and a link extending between said bolster and spring for retaining said spring in a horizontal position. 95

3. In a car truck, a truck frame, a U-shaped hanger, said frame being provided with a recess in its upper edge, an integral projection on said hanger lying in said recess and permitting free swinging movement of the hanger, said hanger being adapted to straddle the frame and extend downward therefrom, a spring seat pivoted to the lower end of said hanger and a leaf spring having its end supported upon said seat. 100

4. In a car truck, a truck frame, a truck bolster, a link pivotally connected thereto, a spring seat on the end of said link, a leaf spring upon which said seat is adapted to rest, supports for the end of said leaf spring, links pivotally connected to said supports and pivotal connections between said last mentioned links and the truck frame. 110

5. In a car truck, a truck frame, a truck bolster mounted therein, a leaf spring, a spring seat resting thereon, a coil spring on said seat for supporting the bolster, a rigid extension on said seat, said extension being pivotally connected to the bolster to maintain the leaf spring in a horizontal position, hangers pivotally connected to the frame and dependent therefrom, and supports 120

pivotedly connected to the lower ends of said hangers and supporting the ends of said leaf spring.

6. In a car truck, a truck frame, a bolster 5 mounted therein, a leaf spring, a spring seat on top of said leaf spring, a rigid extension projecting from said seat and pivotally connected to the bolster, hangers dependent

from the frame, spring seats pivoted to the lower ends of said hangers and supporting 10 the ends of the leaf spring.

Signed at the city and county of Philadelphia, and State of Pennsylvania, this 8th day of December, 1922.

WALTER S. ADAMS.
